UNITED STATES PATENT OFFICE.

ARTHUR R. HARVEY, OF MIDDLETOWN, OHIO.

INSTRUMENT FOR THE AUTOMATIC DETERMINATION OF MOISTURE IN PAPER OR TEXTILES.

Application filed July 11, 1923. Serial No. 650,810.

To all whom it may concern:

Be it known that ARTHUR R. HARVEY, citizen of the United States, residing at Middletown, in the county of Butler and State of Ohio, has invented certain new and useful Improvements in Instruments for the Automatic Determination of Moisture in Paper or Textiles, of which the following is a specification.

- 10 The purpose of the present invention is to provide improved means to indicate, and if desired, to record graphically, the per cent of moisture contained in paper while it is in the process of manufacture. The 15 instrument is designed to be placed in such a position as to determine the moisture content of the paper before its passage to the drier, or at any subsequent time in the manufacture thereof before it is cut into sheets. 20 This instrument might also be used for control purposes, in regulating the quantity of steam admitted to the driers, the quantity of air blown or otherwise admitted to the driers, or for controlling other drying equipment or conditions. The device depends upon heat capacity for its principle of operation.

To my knowledge, there is at present no instrument which gives this result and which depends upon specific heat for its principle. 30 At the present time, moisture content is found by tearing out a sample of the paper and weighing it before and after driving off its moisture by heat. This involves expensive labor, a waste of materials and time (often "breaking down" the paper web in attempt to extract a sample), and what is the most important, a delay of approximately one hour before the result is obtained. An accurate and instantaneous result is therefore of great value in producing a uniform product as well as reducing the cost of manufacture by admitting to and evaporating as little water from the paper 40 as is consistent with the specifications. It is accordingly an object of the present invention to provide an instrument having this advantage.

There are some machines at present which 50 attempt to control drying conditions corresponding to the quantity of water contained in the paper by depending upon the tension resulting when a portion of the water is dried out. This type of machine 55 is however, only applicable to the dry end

of the paper machine as no tension (contraction) results until it is totally or at least partially dried. The advantages of placing a control system ahead of the drier instead of behind it are obvious and it is accordingly an object of the invention to provide a device which may be so placed ahead of the drier. The last named type of machine now in use is objectionable, also, because other factors influence the tension 60 of the paper beside the moisture content thereof.

A further device which has been attempted, depends upon the electrical conductivity of paper to control the drying apparatus. 70 An objection to this method is that the conductivity will be affected by the temperature of the paper and also by the electrolytes in solution in the water contained, it being noted that the water usually contains alum and other salts in varying proportions. The present invention, working upon the principle of heat capacity, will be effective because the heat capacity will not be appreciably effected by any salt dissolved in the water, and is not a function 75 of the initial temperature. The instrument constituting the present invention, is therefore one which possesses inherent advantages 80 not found in prior instruments of this kind. 85

Other objects will appear as the nature of the invention is better understood, and the same consists in the novel form, combination and arrangement of parts herein-after more fully described, shown in the accompanying drawings and claimed.

In the drawings, wherein a preferred embodiment of the invention is shown, and wherein like reference characters indicate corresponding parts throughout the several 90 views,

Figure 1 is a side elevational view of an instrument constructed in accordance with the present invention,

Figure 2 is a front elevational view of the 100 device shown in Figure 1, partly broken away to illustrate details of the invention,

Figure 3 shows a wiring diagram for the heating roll, and

Figure 4 shows a wiring diagram for the 105 temperature measurement roll.

The present device consists essentially of two principal parts, a heating element and a temperature measurement element, the heating element preferably having a constant 110

- and known quantity of heat supplied there-through to the paper, and the temperature measuring element preferably responding to the temperature rise due to the heat input.
- 5 The heating element preferably consists of a roll over which the paper is made to pass, and is preferably heated by electricity so as to provide for accurate heat control, although other means of heating the roll could 10 be utilized, such as steam, hot water, etc. When heated electrically, the roll contains or consists of resistance units so connected to the main that a constant power supply results.
- 15 The temperature measuring device consists of an arrangement of thermo-couples and rolls over which the paper passes, and associated with means which indicates the temperature rise of the paper after passing 20 over the heating roll.
- Referring to the drawings in detail, the roll designated by the reference character 5 represents the heating element, and as shown, has a resistance wire 6 coiled about the inside thereof in the form of a spiral. This resistance is insulated as at 7 from the roll proper by a thin strip of asbestos, and the latter is securely fastened to the internal face of the roll. The ends of the roll may be 25 protected from heat loss by being constructed with a suitable heat insulation such as asbestos or other suitable material, these ends being indicated by the reference numeral 8. The leads 9 from the heating units are 30 brought out through the hollow shaft 10 of the roll 5 and are adapted to be connected with the source of current supply by means of slip rings 11 associated with suitable brushes 12. The heating circuit, as shown in 35 Figure 3, must contain the heating element 6, a watt-meter 13, and a suitable rheostat 14 for controlling the input. The roll itself is preferably constructed of thin metal tubing of the proper diameter.
- 40 The means for obtaining the temperature difference includes rolls 15 and 16 arranged above and at opposite sides of the heating roll 5 and containing thermo-couple junctions 17, the electrical connections to which 45 are made through slip rings 18 to a millivoltmeter or potentiometer 19, as shown in Figure 4. This millivoltmeter or potentiometer is preferably calibrated to read directly in 50 terms of per cent moisture contained in the paper, and the principle involved in this calibration may be mathematically shown as 55 follows:

$$(T_2 - T_1) (W_w \times S_w + W_p \times S_p) = Q$$

60 where

T_2 =temperature of paper after heating

T_1 =temperature of paper before heating

W_w =weight of water contained in the paper plus the weight of dissolved substances

65 S_w =specific heat of above

W_p =weight of bone-dry paper passing over the instrument in unit time

S_p =specific heat of above

Q =Quantity of heat supplied in unit time.

For a given rate of production on the 70 paper machine, all the above factors will be known except W_w (assuming $S_w=1$). The quantity W can therefore be calculated from which the percentage moisture in the paper can be found thus:

$$\frac{W_w}{W_p + W_w} \times 100 = \text{per cent moisture.}$$

The rolls 15 and 16 are preferably supported in such a way that they may be 80 thrown away from the heating roll 5 to provide the necessary clearance for threading the paper about the rolls so as to facilitate starting up of the machine initially, or after a break in the web — W — whose moisture content is to be found. As shown in Figures 85 1 and 2, suitable mounting brackets 20 are provided in which the shaft 10 of the heating roll 5 is journaled, while arms 21 have the shafts of the rollers 15 and 16 journaled 90 therein at the upper ends thereof. These arms 21 are preferably pivotally supported by rock shafts 22 having means generally denoted by the numeral 23 for adjusting the arms 21 in any desired swung position toward or away from the roll 5. One of the rolls 16 is shown by dotted lines in Figure 95 1 as swung in a lowered inoperative position to illustrate this construction.

It is obvious that a suitable scribe may be 100 carried by the pointer of the millivoltmeter or potentiometer 19 and associated with a recording sheet, if a graphic record is desired.

When the heating and temperature measuring elements are combined respectively in single rolls, the resulting moisture content indication will be the mean content across the sheet of paper. However, it is often 105 desirable that the moisture content be known at several different points, and this can be done by breaking up the rolls in several sections arranged end to end and having independent indicating means. In this way, the moisture content will be indicated for the 110 front, back and middle of the web.

An instrument is thus provided whose 115 basic principle depends upon the relationship between the moisture content of the paper and the heat capacity thereof, it being noted that in the device disclosed in the present drawing, a constant rate of heat will be supplied to the roll 5 as the web W moves therearound, and as the temperature indicator 19 is under the influence of the rolls 15 and 16, respectively subjected to the heat of the paper before and after being heated by the roll 5, said indicator will show accurately the moisture content of the paper 120 when calibrated as above described.

Obviously, instead of supplying heat to the heating roll at a constant rate, and measuring the resultant rise in temperature of the paper, the rise in temperature might be 5 fixed and held to a known degree, and a measurement made of the heat necessary to cause this temperature rise. So far as the instruments and their connections go, the two devices would differ greatly, but both 10 would in reality be measuring the heat capacity. It is therefore to be understood that various changes may be made in the construction shown without departing from the spirit and scope of the invention as claimed.

15 From the foregoing description it is believed that the construction and operation of the invention as well as the advantages thereof will be readily understood and appreciated by those skilled in the art.

20 What I claim as new is:

1. In an instrument for the automatic determination of moisture content in a web while moving during its course of manufacture, means for supplying heat to said web, 25 means sensitive to the heat of the web before and means sensitive to the heat of the web after being heated by said heating means, and an indicator controlled by said heat sensitive means for indicating the 30 moisture content of said web.

2. An instrument for the automatic determination of moisture in a web while moving during its course of manufacture, comprising a heating roll about which the web 35 is adapted to be moved, a pair of rolls about which the web is adapted to respectively pass before and after passing around the heating roll, means carried by said second named rolls sensitive to the heat of the web, indicating means and electrical connections with the indicating means and said last named sensitive means for indicating the moisture 40 content of the web.

3. An instrument for the automatic determination of moisture in a web while moving during its course of manufacture, comprising a heating roll about which the web is adapted to be moved, a pair of rolls about 45 which the web is adapted to respectively pass before and after passing around the heating roll, means carried by said second named rolls sensitive to the heat of the paper, and indicating means in electrical connection with said last named sensitive means for indicating the moisture content of the web, 50 said pair of rollers being mounted for swinging movement toward and away from each other and from the heating roll for facilitating threading of the web around said 55 rollers.

60 4. An instrument for the automatic determination of moisture in a web comprising means to supply heat to said web, means sensitive to the heat of said web before and 65 means sensitive to the heat of the web after

being subjected to said heating means, and an indicator actuated by said last named heat sensitive means.

5. In combination, an indicator, an operating means therefor comprising a pair of 70 rotatable elements mounted in spaced relation and adapted for contact and rotation with a movable web, heat responsive means mounted in said elements for contact with said web, responsive to variations in the temperature of the web, and means operatively connecting the heat responsive means with 75 said indicator adapted for operating said indicator to register the percentage of moisture in the web.

6. In combination, an indicator, and an instrument for operating said indicator comprising a base member, a pair of spaced swinging frames hingedly mounted on said base member, rolls rotatably mounted in said 80 frames adapted for contact with a movable web, thermo-couples mounted in said rolls for contact with the web, and connections between the thermo-couple and the indicator for operating said indicator for registering 85 the percentage of moisture in the web.

7. In combination, an indicator and operating means therefor including a pair of spaced rotatable elements adapted to contact and rotate with a movable web, supporting means for said elements, means responsive to the heat of the web mounted in said rotatable elements for contact with said web, and connections with said means and 90 said indicator adapted to operate said indicator to register the percentage of moisture 95 in the web.

8. A device for indicating the percentage of moisture in a web comprising an indicator and controlling means therefor having a 100 pair of heat responsive elements mounted for contact with said web at spaced intervals and operated by the heat of said web at the points of contact of the elements therewith and connections between the indicator and 105 elements for operating said indicator according to the heat in the web on said elements.

9. A device of the class described comprising an indicator, means for supplying a predetermined known quantity of heat to a portion of a movable web and means contacting with the web at spaced intervals, said spaced points of contact being adapted to engage the web at both the heated portion and an unheated portion thereof, and connections between the last mentioned means and the indicator for operating the indicator to register the percentage of moisture in 110 said web.

10. A device of the class described comprising means for supplying heat to a portion of a movable web, means contacting with the web at spaced intervals adapted to engage a portion of the web at the point of engagement by said heat supplying means 115 120 125 130

and an unheated portion thereof spaced from the heating means, an indicator controlled by said last mentioned means, said last mentioned means being sensitive to the heat and changes thereof and connections between the last mentioned means and the indicator for the web, in effecting the control of the indicator by said last mentioned means.

11. A device of the class described comprising means for supplying a predetermined amount of heat to a portion of a web,

heat sensitive means mounted for contact with a portion of the web heated by the first mentioned means and an unheated portion thereof, and an indicator and connections 15 between the indicator and heat sensitive means adapted to operate and control the indicator for registering the percentage of moisture in said web.

In testimony whereof I affix my signature.

ARTHUR R. HARVEY.
